Inventor Walter Hill
By Atty George W. Moore

UNITED STATES PATENT OFFICE.

WALTER HILL, OF SHORT BEACH, BRANFORD, CONNECTICUT.

VENDING-MACHINE.

1,233,357.

Specification of Letters Patent. Patented July 17, 1917.

Application filed April 28, 1916. Serial No. 94,248.

To all whom it may concern:

Be it known that I, WALTER HILL, a citizen of the United States, residing at Short Beach, town of Branford, in the county of New Haven and State of Connecticut, have invented certain new and useful Improvements in Vending-Machines, of which the following is a specification, reference being had therein to the accompanying drawings.

10 My invention relates to a new and improved vending machine, referring more particularly to a machine for automatically selling small articles, such as candies, chocolates, chewing gum, etc., although it may be used equally as well for vending articles of a similar nature.

15 It is the object of my invention, among other things, to produce a vending machine that is so designed and constructed that a plurality of such articles may be separately contained within said machine and the mechanisms for each of said separately contained articles shall be independent of each other, whereby it may be assembled or taken down without disturbing adjacent mechanisms; to so mount such mechanism that it may be readily exposed for purposes of examination, repairs, etc.; and in numerous other ways to modify the mechanism of this 20 type of machine that it may be economically constructed, readily assembled and operate with certainty, although subject to the roughest kind of usage; all of which will more particularly appear from the following specification.

25 To these, and other ends, my invention consists in the vending machine, having certain details of construction and combinations of parts, as will be hereinafter described and more particularly pointed out in the claims.

30 Referring to the drawings, in which like numerals of reference designate like parts in the several figures;

35 Figure 1 is a side elevation of the interior mechanisms of one of the units of my improved machine, with the case and some of the parts in section;

40 Fig. 2 is a sectional elevation of the coin chute, taken substantially upon line 2—2 of Fig. 4;

45 Fig. 3 is a diagrammatic sectional view of the body member and the front and rear plates, taken substantially upon line 3—3 of Fig. 1;

Fig. 4 is a rear view of the interior mechanism of my improved device;

Fig. 5 is an enlarged sectional view thereof, taken upon line 5—5 of Fig. 1;

Fig. 6 is a detail view of the shutter for the coin slot;

Fig. 7 is a plan view of two members of the coin twister, shown separated from each other;

Fig. 8 is a sectional view of the twister, taken upon line 8—8 of Fig. 7, its two members being in contact with each other; and

Fig. 9 is a fragmentary view of some of the parts showing one of the relative positions of the coin, ejecting lever and carrier shaft.

In the practice of my invention I provide a body member 1, to the rear end of which is hinged a back plate 2 that is secured in a reasonably permanent manner to a fixed member, and to the front of which is hinged a front plate 3, the back plate being secured at its free end to said body member by a catch 4, which engages a lug 5 upon the inside of the body member, and the front plate 3 is secured by a lock 6 of any preferred form.

With this method of constructing the body member and front and rear portions thereof the interior mechanism can be readily exposed for the purpose of replacement, alterations, repairs, etc., without taking down the entire device from the member to which it is attached. Fixed within the case, in any preferred manner, is the supporting plate 7. Attached to the upper end of this plate is a coin chute 8, the opening 9 therein registering with a coin opening 10 in the front plate 3. This opening 9 extends in substantially a right angle direction through the coin chute 8, terminating at the bottom end at the opening 10 and having one open side 11 adjacent to which is fixed a magnet 12.

The coins are placed in the coin chute through the opening 10 and into the opening 9, and if they are of the proper size, and not made of iron or steel, they will ride upon the bottom edge of said opening 9, and in the path shown substantially by the coin outlined in dotted lines in Fig. 1, and are discharged therefrom through the opening 73. If, however, an iron or steel disk is placed in the chute instead of a coin, the magnet 12 deflects them from the path traveled by the coin sufficiently to cause the

same to jump out of said coin chute through the opening 11 into the slug box 13 fixed to the back plate 2.

5 A wing 14 fixed to the side of the coin chute is so arranged as to direct a coin or article brought in contact therewith into the slug box 13 if it should escape through any of the openings therein except openings 10 and 11.

10 Fixed to the plate 7 is a coin twister designed to turn the coin through an angle of 90°, so as to present it to the operative mechanism of the device at substantially a right angle to the direction in which it entered the coin chute. This twister mechanism comprises the members 15 and 16, which are semi-circular in cross section and have overlapping lips 17 and 18 thereon that coöperate to prevent lateral movement 15 of the members in relation to each other.

15 The member 15 is provided with a recess 19 therein, the bottom of which forms an inclined plane 20, and the member 16 is provided with a recess 21, which is provided 25 with a bottom forming the inclined plane 22, the incline being directed toward the inner face of said member 15, as shown in Fig. 8, and toward one side, as shown in Fig. 4, and terminating at the bottom in the recess 23 of substantially uniform width and depth.

20 The members 15 and 16 are assembled within a ring 24 with the bands 25 resting thereon and said ring 24 being secured to the plate 7 by the standard 26.

25 The coins drop from the coin chute into the recesses 19 and 21 in the twister mechanism, and by reason of the inclined bottom 22 within the member 16, the coin is turned 30 through an angle of 90° while passing through said twister mechanism, and before it enters the recess 23.

35 Journalized in the brackets 28, fixed to the plate 7, is a coin carrier shaft 27, having a stop lug 31 thereon, with grooved wheel 29 fixed upon one end thereof, and preferably integral with said shaft are a plurality of wings 30 arranged in pairs, each pair being 40 equally distant from the center of the twister mechanism above described.

45 These wings in cross section are substantially right angle in shape so as to prevent lateral movement of the coin therein. Also rotatably mounted in the brackets 28 is the 50 trip shaft 32 having a counter-balance weight 33 threadably secured therein, whereby it may be adjusted so that the shaft 32 may be actuated by a predetermined weight.

55 Secured to said shaft 32 and projecting radially therefrom are a plurality of trip fingers 34, which project at their outer ends over the shaft 27 and between the wings 30.

60 Adjustable on the shaft 32 is a collar 35 having a lock bar 36 fixed therein which 65 projects radially therefrom into the path of

movement of the stop lug 31, which it engages when the parts are at rest and substantially as shown in Fig. 1, the weight 33 holding said lock bar 36 in engagement with the stop lug 31 and preventing rotation of 70 the shaft 27 in one direction.

Attached to the plate 7 is the bracket 37, to which is secured the ejecting lever 38 by the bolt 39, said ejecting lever having a notch 40 in its upper end and adjacent thereto, a coin deflecting flange 41, and the lower end of which is pivotally secured to a slide 42 carrying the pivotally mounted push lever 43 having a head 44 thereon.

Also fixed to the plate 7 upon the side 80 thereof opposite to the mechanism hereinbefore described, are a plurality of containers 45 designed to hold articles to be sold, and in cross section have a lengthwise opening therethrough of substantially the same shape 85 as that of the article to be vended so that the same may be readily placed therein and lie within a column one above the other. Movably mounted therein upon the top of said articles is a weight 46 having a pin 47 secured therein. The articles to be vended are designated in Fig. 1 by the numerals 48, the bottom article in the column resting upon the supports 49, which are spaced a sufficient distance apart to permit the head 90 44 of the push lever 43 to pass therebetween.

95 Pivoted to the body member 1 by the pintle 50 is the bell crank lever 51, the lower arm of which projects through the bottom of the body member 1 and has a finger plate 52 at its lower extremity. To the outer end of the other arm is pivoted a block 53, within which is adjustably secured the connecting rod 54 by means of the jam nuts 55, the free end of said projecting rod being connected with a chain 56, which is fixed to the grooved wheel 29 by a screw 57 or other convenient means, and to the opposite end of which is a spring 58 attached at its lower end to a pin 59 in the body member 1.

100 As the coin drops by gravity from the twister mechanism, it engages the outer end of the trip fingers 34, and by its weight rocks the shaft 32 and releases the lock bar 36 from the stop lug 31, in which position the 105 coin lies between the wings 30 which prevent its lateral movement.

110 The bell crank lever 51 is now normally actuated by engaging the finger plate 52, and through the connection rod 54 and chain 115 56 a rotary movement is imparted to the shaft 27 and the coin carried about the axis of said shaft until it passes over the outer end of the trip fingers 34, at which time said coin is held against lateral movement by 120 said wings and against an upward movement by the lugs 60, as shown in Fig. 4, and one face of the coin then engages the upper end of the ejecting lever 38, the lip 61 on said lever projecting over the top of the coin. 125

The ejecting lever is now rocked upon its pivot mounting until it assumes the position shown by broken lines in Fig. 1, during which time the slide 42 has moved forward 5 carrying with it the push lever 43, and the head 44 engages the bottom article in the column within the container 45 and knocks the same therefrom, which is delivered through the slot 62.

10 When the ejector lever is in the position substantially shown by dotted lines in Fig. 1, the article has been completely ejected and the coin drops by gravity out from between the wings 30 onto the flange 41 and is deflected 15 into the coin receptacle 63 which rests upon the brackets 37 between the plate 7 and the several levers 38.

The spring 71 fixed to the plate 7 contacts 20 with the ejecting lever 38 and always exerts its tension so as to move the upper end of said lever toward the shaft 27.

Upon releasing the lever 51 the spring 58 returns it to the position shown by full lines in Fig. 1, at which time the push lever 43 25 is tilted to the position shown by broken lines in said figure and the head 44 passes underneath the column of articles without imparting movement thereto and after being disengaged therefrom the weighted end 30 64 of said lever causes the same to rock upon its pivot mounting again and assume the position shown by full lines in Fig. 1. During this movement the shaft 27 is returned to its original position and the lock 35 bar 36 engages the stop lug 31 and is held therein by the counter-balance 33.

The relative position of the upper end of the ejecting lever 38, with the wings 30 upon the shaft 27, is such that when the coin begins 40 to move about the axis of the shaft 27, by reason of the pull upon the crank lever 51, the ejecting lever is rocked by the coin until the outer edge thereof passes under the shoulder 72 and the spring 71 returns the lever 45 38 and the parts connected therewith to their original positions and the lever pushes the coin into the coin receiver if it has not already dropped therein. The article will not be moved out of the container by the head 50 44 until the outer edge of the coin has substantially reached the shoulder 72, as shown in Fig. 9, so that the article is delivered before the coin passes from the coin carrying mechanism, thus preventing delivery of more 55 than one article for a single coin. If, however, the crank 51 is released before the article is delivered and before the coin has become disengaged from the coin carrying mechanism, the spring 71 will return the lever 60 38 to the position substantially shown by broken lines in Fig. 1, carrying with it the coin so that it is returned to the position approximating that assumed by it after it has begun its rotary movement with the 65 coin shaft 27.

It will be remembered that as soon as the coin begins to rotate with the shaft 27, that the coin passes over the end of the trip finger 34, thus permitting the shaft 32 to rock and return the lock bar 36 to its engagement 70 with the stop lug 31 upon the shaft 27, thus preventing a further rotation of said shaft while a coin is therein and not discharged therefrom. Hence the shaft 27 cannot be again rotated with a new coin while there 75 is a coin undelivered therefrom, thus obviating the procuring of more than a single article for a single coin.

Pivots mounted to the flange 65 is the shutter 66 having a slot 67 therein that registers with the coin slot 10 when in one of its positions, having an arm 68 thereon which rests upon the upper end of a slide rod 69, which is connected with the pivotally mounted lever 70, one end of which is in the path 80 of movement of the pin 47.

As the last article in the column is ejected in the manner hereinbefore described, the pin 47 contacts with the lever 70 and moves the slide rod 69 upwardly, rocking the shutter 66 so as to move the slot 67 therein out of register with the coin opening 10, at which time it will be impossible to place a coin in the chute.

With a device designed as hereinbefore 95 described any number of containers may be arranged within a body member, the mechanism connected therewith for ejecting the articles in each of them being separate and independent from that of the other containers.

The mechanism itself is extremely simple, is readily assembled and so mounted as to be accessible from the front or rear of the machine, and so far as ingenuity can devise, it 105 is subject to the minimum liability to injury by reason of unlawful tampering therewith.

There are minor changes and alterations that may be made within my invention, aside from those herein suggested, and I would therefore have it understood, that I do not limit myself to the exact construction herein shown and described, but claim all that falls fairly within the spirit and scope of the appended claims.

Having described my invention, what I claim as new and desire to secure by Letters Patent, is:—

1. In a device of the character described, the combination with a coin chute; of a rotary member having means connected therewith for holding a coin; and means between said coin chute and said member for rotating said coin through an angle of substantially 90° , said means comprising companion 120 members and each having a recess therein, and means for holding said members in a fixed position in contact with each other, and when so held having a single opening therebetween formed by said recesses. 125 130

2. In a device of the character described, the combination with a first shaft; of means connected therewith for holding a coin thereon; means for manually imparting movement to said shaft; a second shaft; a trip finger connected therewith and projecting over said first shaft adjacent to said coin retaining means; a stop member connected with said second shaft and engaging a part 5 in one direction; a plurality of trip fingers corresponding in number with said containers and projecting over said first shaft between said wings; means for delivering a coin onto each of said trip fingers and between said wings and by reason of its weight actuating said companion shaft and disengaging the part connected therewith from said first shaft so that the same may be rotated, a lever lying in the path of movement 70 of said coin when between said wings and while being rotated with said first shaft, a slide connected with said lever and actuated thereby, a push lever pivotally mounted on said slide and when moving in one direction contacts with the lower article in the container and ejects the same therefrom. 75
- 10 3. In a device of the character described, the combination with a first shaft; of means connected therewith for holding a coin thereon; means for manually imparting movement to said shaft; a second shaft; a trip finger connected therewith and projecting over said first shaft adjacent to said coin retaining means; a stop member connected with said second shaft and engaging a part on said first shaft to limit the rotation 80 of said latter shaft in one direction; and means for delivering a coin onto said trip finger and releasing the stop member from its engagement with the first of said shafts. 85
- 15 4. In a device of the character described, the combination with a first shaft; of means connected therewith for holding a coin thereon; means for manually imparting movement to said shaft; a second shaft; a trip finger connected therewith and projecting over said first shaft adjacent to said coin retaining means; a stop member connected with said second shaft and engaging a part on said first shaft to limit the rotation 90 of said latter shaft in one direction; and means for delivering a coin onto said trip finger and releasing the stop member from its engagement with the first of said shafts; a container; a slide movable in a path at an angle to said container; a push lever pivotally mounted on said slide; and a rock lever having engagement with said slide with a part thereon adjacent to the said coin holding means. 95
- 20 5. In a device of the character described, the combination with a first shaft having coin holding means connected therewith which prevent lateral movement of a coin in relation thereto; a second shaft substantially parallel therewith; a trip finger connected with said second shaft and projecting over said first shaft; means connected with said second shaft and engaging a part on said first shaft to limit the rotation 100 thereof in one direction, the relation of said trip finger and said last mentioned means being such that when said trip finger is depressed by reason of the weight of a coin thereon, said means will be disengaged from said first shaft; and means for manually rotating said first shaft. 105
- 25 6. In a device of the character described, the combination with a plurality of containers arranged so as to hold a column of articles therein; and means for successively pushing the bottom article in said column from said containers, said means comprising a first shaft having a plurality of wings connected therewith, said wings being arranged in pairs and there being as many pairs as there are containers; means for manually rotating said shaft in one direction; a companion shaft; a member connected with said companion shaft and engaging a part upon 110 said first shaft to limit the rotation thereof in one direction; a plurality of trip fingers corresponding in number with said containers and projecting over said first shaft between said wings; means for delivering a coin onto each of said trip fingers and between said wings and by reason of its weight actuating said companion shaft and disengaging the part connected therewith from said first shaft so that the same may be rotated, a lever lying in the path of movement of said coin when between said wings and while being rotated with said first shaft, a slide connected with said lever and actuated thereby, a push lever pivotally mounted on said slide and when moving in one direction contacts with the lower article in the container and ejects the same therefrom, said push lever being so connected with said slide that when moving in one direction it will eject the bottom article in said container and while moving in the opposite direction will pass underneath the entire column of articles within said container. 115
- 30 7. In a device of the character described, the combination with a plurality of containers arranged so as to hold a column of articles therein; means for successively pushing the bottom article in said column from said containers, said means comprising a first shaft having a plurality of wings connected therewith, said wings being arranged in pairs and there being as many pairs as there are containers; means for manually rotating said shaft in one direction; a companion shaft; a member connected with said companion shaft and engaging a part upon 120 said first shaft to limit the rotation thereof in one direction; a plurality of trip fingers corresponding in number with said containers and projecting over said first shaft between said wings; means for delivering a coin onto each of said trip fingers and between said wings and by reason of its weight actuating said companion shaft and disengaging the part connected therewith from said first shaft so that the same may be rotated, a lever lying in the path of movement of said coin when between said wings and while being rotated with said first shaft, a slide connected with said lever and actuated thereby, a push lever pivotally mounted on said slide and when moving in one direction contacts with the lower article in the container and ejects the same therefrom, said push lever being so connected with said slide that when moving in one direction it will eject the bottom article in said container and while moving in the opposite direction will pass underneath the entire column of articles within said container. 125
- 35 8. In a device of the character described, the combination with a plurality of containers arranged so as to hold a column of articles therein; and means for successively pushing the bottom article in said column from said containers, said means comprising a first shaft having a plurality of wings connected therewith, said wings being arranged in pairs and there being as many pairs as there are containers; means for manually rotating said shaft in one direction; a companion shaft; a member connected with said companion shaft and engaging a part upon 130 said first shaft to limit the rotation thereof in one direction; a plurality of trip fingers corresponding in number with said containers and projecting over said first shaft between said wings; means for delivering a coin onto each of said trip fingers and between said wings and by reason of its weight actuating said companion shaft and disengaging the part connected therewith from said first shaft so that the same may be rotated, a lever lying in the path of movement of said coin when between said wings and while being rotated with said first shaft, a slide connected with said lever and actuated thereby, a push lever pivotally mounted on said slide and when moving in one direction contacts with the lower article in the container and ejects the same therefrom. 135

panion shaft; a member connected with said companion shaft and engaging a part upon said first shaft to limit the rotation thereof in one direction; a plurality of trip fingers 5 corresponding in number with said containers and projecting over said first shaft between said wings; means for delivering a coin onto each of said trip fingers and between said wings and by reason of its 10 weight actuating said companion shaft and disengaging the part connected therewith from said first shaft so that the same may be rotated, a lever lying in the path of movement of said coin when between said 15 wings and while being rotated with said first shaft, a slide connected with said lever and actuated thereby, a push lever pivotally mounted on said slide and when moving in one direction contacts with the lower article 20 in the container and ejects the same there-

from, and means for preventing the insertion of a coin in said mechanism when all of the articles in said columns shall have been ejected therefrom, said means comprising a pivotally mounted shutter adjacent to the coin lever; a pivotally mounted lever; a weight within each of said containers that rests upon the top of the articles therein; a connection between said lever and shutter; a weight within each of said containers and resting upon the top of the articles in said containers and having a part thereon which engages said lever and actuates said shutter so as to cover the said coin opening when all of the articles in the said 35 containers have been ejected therefrom.

In testimony whereof I have hereunto affixed my signature.

WALTER HILL.
